UNITED STATES PATENT OFFICE

SIMON BOLIN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS

LOOM

Application filed November 25, 1929. Serial No. 409,508.

This invention relates to improvements in looms and it consists of the matters herein-after described and more particularly pointed out in the appended claims.

- 5   The primary object of the invention is to provide a loom which is universal in effect, in that either plain or patterned fabric may be rapidly woven and with which the fabric may be made in any width up to the full size
 10 width capable of being produced by the loom and this without necessity of pulling such warps as are not required in the chosen width of fabric and thereby eliminating subsequent rethreading of the pulled warps
 15 when a wider fabric is to be produced.

Another object of the invention is to provide a loom having a novel shed forming mechanism including heddles of peculiar construction capable of being actuated to 20 produce either plain or patterned fabric and any one or more of which heddles may be rendered inoperative to produce sheds, when a fabric less than one of full width is desired.

25   A further object of the invention is to provide a loom wherein the pattern card mechanism controlling the operations of the heddles and associated neck bars may be actuated to repeat the patterns at desired intervals whereby a greater pattern effect may be 30 attained with but a few pattern control cards.

Still a further object of the invention is to provide a loom having novel means for 35 checking the rebound of the weft upon insertion thereof when relatively stiff wefts are employed in the fabric, as well as other novel means for straightening such relatively stiff wefts after they are incorporated in 40 the fabric, by blasts or jets of compressed air.

The above mentioned objects of the invention as well as others, together with the many advantages thereof will more fully appear as I proceed with my specification.

The invention is herein illustrated and described as embodied in a loom for weaving a stake and strand fabric of reed or the like wherein the stakes or wefts are relatively stiff when compared with the strands or

warps, the fabric mentioned being especially adapted as the covering for the frame structure of certain vehicles and articles of furniture. However, it is to be understood that the invention is not to be limited to a loom 55 solely for such fabric because, as is apparent the invention may also be embodied in looms for other kinds of fabric, where its characteristics make it desirable.

In the drawings:—

Fig. 1 is a right hand side elevation of a loom constructed in accordance with one embodiment of the invention.

Fig. 2 is a left hand side elevation of the same.

Fig. 3 is a fragmentary top plan view of the same.

Fig. 4 is a vertical longitudinal section of the same on the line 4—4 of Fig. 3.

Fig. 5 is a detail vertical section showing 70 the shedding and pattern controlling mechanisms of Fig. 4 on an enlarged scale.

Figs. 6, 7 and 8 are views similar to Fig. 5 showing various parts of the mechanism in different positions.

Figs. 9 to 13 inclusive show the sprockets of the pattern control mechanism and in side elevation and in various positions.

Fig. 14 is an enlarged detail vertical sectional view showing one element of the pattern control mechanisms associated elements for forming the sheds.

Fig. 15 is a detail side elevation showing a series of the shed forming heddle plates embodied in the loom.

Fig. 16 is a sectional view on the line 16—16 of Fig. 15.

Fig. 17 is a fragmentary view in side elevation showing the stake feeding rolls and certain of the heddle plates of the loom in their 90 relative positions.

Fig. 18 is a perspective view showing the cushioning means disposed in the path of the stakes fed by the rolls of Fig. 17.

Fig. 19 is a detail view in side elevation 95 showing the compressed air feed pipes and valve of the loom and the valve operating cam.

Fig. 20 shows the compressed air distributing pipe and discharge nozzles thereof. 100

Fig. 21 is a fragmentary detail perspective view showing the position of the air discharge nozzles with respect to a stake upon which compressed air is directed, to straighten the same.

Fig. 22 is a perspective view of a part of the pattern chain of the loom and associated means for producing the desired pattern.

Fig. 23 is a detail end elevation showing a sprocket and part of a pattern chain thereof.

Fig. 24 is a fragmentary detail view showing the device for locking the pattern control card of a pattern chain plate against movement relatively to the latter.

Fig. 25 is a sectional view on the line 25—25 of Fig. 24.

Fig. 26 is a side elevation showing a set of shift plates and pins of the pattern control mechanism.

Fig. 27 is an end elevation of the same.

Figs. 28 and 29 are front elevations showing various pattern control cards for association with the sprocket chain plates of the loom for producing various patterns.

Figs. 30, 31 and 32 are fragmentary views showing pieces of stake and strand reed fabric capable of being produced by the loom of this invention.

Fig. 33 is a side elevation of an attachment which is used when relatively long pattern chains are employed and Fig. 34 is an end view of the mechanism shown in Fig. 33.

Fig. 35 is a transverse detail sectional view on an enlarged scale as taken on the line 35—35 of Fig. 5 and shows the positions of the stake inserting and rebound preventing means at opposite sides of the loom.

The loom comprises a suitable frame including side plates 1—1 which carry the bearings for the main or drive shaft 2, the latter being operatively connected by means of the pinion 3 and spur gear 4 with the main counter shaft 5 (Fig. 4). The latter is geared by means of sprocket wheels and the chain 6, to a counter shaft 7, which is associated with the heddle operating shaft 8 by means of spur gears 9 and 10.

The shaft 8 carries an eccentric 11 at each end, the associated strap 12 of which is pivotally connected to the bottom end of a vertically disposed reciprocable plunger 13, one adjacent each side plate 1 of the loom. Both plungers are rigid with a horizontally disposed, transverse cross bar 14 mounted upon the upper end portions thereof. Each plunger 13 is also rigid with a vertically guided rack bar 15 one at each side of the loom which meshes with a pinion 16 on a stud shaft 17 each carried by one of a pair of upright extension frame members 18 mounted on the side plates 1. Each pinion 16 also meshes with a vertically guided rack bar 19 rigid with a cross bar 20 which constitutes a companion element to the bar 14. Said bars 14 and 20 are slidably mounted at their ends

in guides on the frame members 18. Obviously said bars 14 and 20 are thus caused to move simultaneously in opposite directions. Each bar is equipped along its upper edge with a flange 21, said flanges being opposed to each other and engaging in the recesses 22 of the neck bars 23 which are pivotally associated with the heddle plates 24.

Referring now to Figs. 5, 6 and 7, it will be noted that the neck bars 23, which consist of relatively thin flat plates, are provided at their upper ends with heads 25 and, at their lower ends with arcuate projections 26, the latter engaging in corresponding recesses in the upper ends of the heddle plates 24. Said heddle plates are of substantially the same thickness as the neck bars 23 and are reciprocated by the latter as hereinafter described.

The heddle plates 24 are disposed in surface contact or substantially in surface contact with each other and are mounted along their upper and lower end portions, along one margin in guide grooves of opposed pairs of cross frame members 27 and 28. Said cross frame members are arranged parallel with each other with their respective guide grooves disposed in staggered relation to each other. Thus one heddle plate will be disposed along its rear margin in guide grooves in the rear frame members while its front margin will be disposed in contact with ribs between adjacent grooves of the opposite frame members. The next adjacent heddle plate would be engaged with its front margin in guide grooves of the last named frame members and its rear margin in contact with ribs of the first named frame members as will be readily understood by persons skilled in the art.

Owing to the fact that, alternate sets of the heddle plates and neck bars are of different lengths with respect to intermediate sets as is apparent from Fig. 5, the pivotal associations thereof with the respective neck bars will not permit of any relative lateral movement of any neck bar with respect to its heddle plate so that there can be no release or interference with these pivots during the operation of the loom.

Each heddle plate 24 is provided between its ends with a slot 29 extending from front to rear edge thereof and of a width equal to the thickness of the plate, said thickness being of substantially the diameter of the strands which pass through said slots. Each slot is spanned by an integral bridge piece 30 which is bowed and projects from one face of the plate. The said slots extend angularly of the front and rear edges of the plates 24 and in intersecting relation to each other with respect to contiguous plates. In other words the slots 29 of alternate heddle plates 24 extend downwardly from the rear to the front edges thereof and in the intermediate

plates they extend upwardly from the rear to the front edges thereof and therefor can overlap each other without registration. The said plates are arranged in pairs and the bridge pieces 30 thereof are disposed adjacent the rear end of the associated slot 29. Alternate plates 24 are each provided with an elongated opening 31 below the bridge piece 30, while the intermediate plates are each provided with a similar slot 31 above the bridge piece. The disposition of the bridge pieces 30 and slots 31 in the respective heddle plates permit the travel of the bridge pieces 30 in the respective plates to that extent required for the relative reciprocatory movement of said plates in opposite directions. The slot 31 of the plates 24 of one pair will be offset from the slot of the plates of the other pair a distance sufficient to permit of the necessary stroke or movement of the parts.

In order that the front edges of the heddle plates 24 may be flush with each other above and below the front ends of the slots 29, alternate plates are there provided with recesses of a depth equal to that of the guide grooves of the members 27 and 28.

The alternate, opposite angularity of the slots 29 of the plates 24 accomplishes several desirable purposes in that it prevents a strand passing through the slot 29 of one plate from moving laterally into or partially into the slot 29 of an adjacent plate 24 and thereby also prevents any shearing action by the edges of the slot of one plate upon a strand 1^a, engaged in a slot of an adjacent plate.

Associated with the heddle plates are the guide rolls 32 (Fig. 4) geared to rotate in unison in respectively opposite directions and provided with angular grooves to receive and space the strands 1^a apart. The grooves of said respective rolls are staggered so that said strands engaged in the grooves of one roll will pass through slots 29 of alternate plates 24. Associated with the rolls 32 is a perforated guide plate 33 having an upper row of perforations aligned with the annular grooves of the upper roll 32 and the lower line of perforations aligned with the grooves of the lower roll 32. The strands 1^a are fed from spools or reels (not shown) which correspond in number with that of the strands employed in the fabric being produced. In the instance illustrated the guide plate 33 is the upstanding flange of an angle iron 34 which is rigidly mounted upon the machine frame.

The strands 1^a are pulled through the perforations of the plate 33 and through the slots 29 of the heddle plates 24 by means of rolls 35, the shaft or trunnions of which are journalled in bearings on the side plates 1 and which are suitably geared to rotate in opposite directions at the same peripheral speed. These rolls have longitudinally cor-

rugated surfaces, the corrugations of which preferably correspond in spacing with the convolutions or hills and valleys as they are sometimes called, of the finished fabric which passes over the first and under the second of said rolls and is then wound upon a take-up roll (not shown).

Referring now to Fig. 1, it will be noted that the shaft 5 is equipped at one end with a crank 36 associated by means of the pitman 37 with the rocking arm 38 loosely mounted on the shaft or trunnion of one of the rolls 35. A ratchet wheel 39 is rigid with the latter and is engaged by the spring held dog 40 pivotally mounted in the forked end of the pitman 37 for imparting intermittent movement to said rolls 35, reverse rotation of the latter being prevented by the spring held dog 41.

The crank pin with which the pitman 37 is engaged projects from the face of a cam 42 on the shaft 5. A spring 43 holds the anti-friction roller of the rocking lever 44 in surface contact with said cam which imparts rocking movement thereto to open and close a valve in the casing 45 interposed in the compressed air feed pipe 46. The latter connects with a discharge pipe 47 for compressed air which is equipped with a series of air discharge nozzles 47^a so disposed as to cause the jets of air to impinge the stakes 1^b of the fabric directly after they are passed into the sheds formed successively by the strands as best shown in Fig. 4. These air jets forcibly project said stakes against the plain, flat surface formed by the front edge portions of the heddle plates adjacent the rear ends of the slots 29 thereof to assure proper positioning of each stake in the shed and, more particularly, to straighten the stake an instant before the same is engaged by and bound between the two sets of strands of the shed.

Associated with the neck bars 23 are shift plates 48, pattern chains 49 and sprockets 50. The shift plates 48 are disposed side by side, there being one thereof engaged with each neck bar 23. Said plates 48 are reciprocable in suitable guides of a frame disposed transversely of the direction of reciprocation of said neck bars. Thus each plate 48 is provided in its lower edge with a deep recess 51 in which the head 25 of a neck bar remains engaged at all times.

Each shift plate 48 is provided at its opposite ends with extensions 48^a to engage pins 52 having guided sliding movement in cross plates 52^a fixed on the top ends of the frame member 18. Said pins have reduced outer end portions opposed to the faces of the plates of the pattern chain 49. The plates 48 may be regarded as comprising sets of six each and the extensions 48^a thereof are equally spaced from each other vertically to permit of similar spacing of the pins 52 so

that said pins will register with the perforations in the pattern chain plates.

The pattern chains may consist each of a number of links as, for example, eight thereof. The sprockets 50 are square in cross sections and hollow, the walls thereof being provided with perforations registering with those of the pattern chain plates and the pins 52 of the shift plates with which said perforations are axially aligned.

The pattern plates and the walls of the sprockets are also provided with interengaging pilot formations 53—54 (Fig. 23) adapted to maintain said elements relatively positioned so that the respective perforations thereof will register.

Along the upper and lower edges of the pattern plates there are grooves or channels to receive pattern cards 55 which contain certain perforations for register with those of the pattern chain plates, but are blind with respect to other of the perforations comprised within the area covered by said cards 55. Each card 55 is secured against lateral movement relatively to a pattern chain plate by means of an eyelet 56 which engages in a pair of registering perforations and is provided at one end with an annular flange and at its other end with a pair of bendable ears or projections 57.

As best shown in Fig. 3, the shift plates 48 are disposed in close side by side arrangement and have no associated springs to urge them in one direction or the other. Therefore, they are incapable of movement unless positively actuated by the engagement of their end pins 52 with the associated parts of the pattern cards in the plates of the chain 49. By reason of this construction it is possible to use only a short pattern card in each plate of the chain where only a narrow pattern band is wanted in the fabric and these short cards may be readily shifted to any position in said plates to dispose said pattern band in the desired location in said fabric. By such an arrangement the pattern cards to be used need only be as long as the width of the desired pattern band in the fabric and much time and labor is saved in preparing such short pattern cards over cards of a length equal to that of the chain plates. In this manner it is not necessary to make a complete change of pattern cards as is now necessary in jacquards that employ a spring tension on the neck cards or equivalent devices.

The sprocket 50 at one side of the guide frame for the shift plates 48 is carried by one of two pairs of reciprocable rack bars 58—59 slidably mounted in guides in the frame members 18, and the other is carried by the other of said pairs of rack bars, said sprockets having axial trunnions rotatably associated with said rack bars. An idle pinion 60 meshes with the teeth of opposed pairs of rack bars

58—59 so that the reciprocation of opposed pairs of rack bars 58 is transmitted to the rack bars 59 to cause them to move simultaneously in opposite directions thereby causing the sprockets 50 to reciprocate toward and from each other. The motion toward each other is of such stroke as to cause the reduced end portions of the pins 52 associated with the shift plates 48 opposed to said sprockets 50 to project thru the perforations of the pattern chain plates then covering the wall of the sprocket moving toward said pins and also through the similar perforations of said wall of said sprocket. In the event that any of said perforations are covered by the imperforate part of the cards 55, then the pins 52 opposed said covered perforations will contact with the faces of said cards. This will cause the plates 48 with which they are associated to be shifted to thereby throw the associated neck bars 23 from engaging relation with one of the members 14 and 20 into engaging relation with the other thereof.

In the producing of regular over and under stake and strand fabric, alternate neck bars are associated with and actuated or reciprocated by the cross bar 14 and the intermediate neck bars are associated with and actuated or reciprocated by the cross bar 20. It is pointed out that the recesses 22 in the neck bars are of a greater vertical length than are the flanges 21 which engage therein. By means of this arrangement, a lost motion connection is had between said neck bars and the bars 14 and 20 in that the said flanges only act at the ends of their strokes to impart movement of the neck bars. In this manner the neck bars and heddle plates are passive and remain stationary during the insertion of the stakes and this lost motion also permits moving the neck bars manually into a neutral plane between said flanges when the loom is in operation whereby the heddles are rendered inoperative when so desired. Thus as certain of the alternate neck bars are shifted from that position wherein they are engaged by the bar 14 to that position wherein they are engaged by the bar 20, it is apparent that the plurality of adjacent neck bars will act simultaneously to shift corresponding heddle plates in producing a shed so that the strands engaged with said plates will be disposed in side by side relation upon one side of an inserted stake. Thus a contrast is produced in the finished fabric between the regular over and under weave and the band like weave thus produced. By means of the proper disposition as well as absence of openings in the pattern cards, several sections of which are shown in Figs. 28 and 29 it is apparent that any desired pattern capable of being delineated by band portions may be produced. In this respect attention is called to Fig. 30 wherein certain groups of band like areas are produced in the regular over and under

weave. Said areas being substantially of diamond like design.

In Fig. 31 a single band is shown in the fabric, produced by laying five strands over and under adjacent stakes and in Fig. 32 a plurality of such bands is shown, as produced by laying five strands over and under adjacent stakes in alternation.

Levers 65 are disposed below said dogs and are pivotally supported between their ends on the frame members 18, to control the engaging relation of the dogs 62 with respect to the sprocket pins 61, each of said levers 65 being equipped at its outer end with a projection 66 which normally limits the downward movement of said dogs.

When said levers are pivotally swung, their outer ends 66 act to throw said dogs 62 out of engaging relation with said pins 61. The inner ends of said levers 65 are normally disposed in contact with the lower end of a plunger 67 which is depressed by detachable cam members 68 carried by the sprocket chain 69 disposed upon sprocket wheels 70 suitably rotatably mounted on the machine frame. One of said sprockets is non-rotatable relatively to a ratchet wheel 71 which is arranged to move the chain a distance equal to the length of one of its links at each rocking movement of the dog 72 in one direction, said dog 72 being carried by a rocking arm 73 pivotally associated with the shaft of the lower sprocket wheel and the ratchet 71 said lever 73 being operatively associated with the rack bars 58-59 for actuation thereby. When the plunger 67 is engaged by a cam member 68 of the chain it is depressed thereby to thus rock the lever 65 to a position to throw the dogs 62 out of engaging relation with respect to the sprocket pins thus preventing rotation of the sprockets 50 as will be obvious. Thus in the operation of the loom the pattern produced by the cards arranged for engagement by the pins 62 may be repeated so long as the members 62 are held out of engagement with the sprocket pins 61. This is best illustrated in Figs. 9 to 13 inclusive.

Each rack bar 59 is also engaged by a segmental spur gear 74, there being one of such gears 74 at each side of the loom. Each gear 74 is rocked by means of an associated crank 75, pitman 76 and the crank 77 on the shaft 7 before mentioned.

Referring now to Figs. 17, 18, and 35, it will be noted that the stakes 1^b of the fabric are projected successively into the sheds formed by the strands of the fabric by means of the feed rolls 78 and 79 disposed at one side of the loom as best shown in Fig. 2. Said rolls rotate continuously at high speed, and each stake which may be fed to them in any suitable manner is engaged between the same and projected into each shed as it is formed. Disposed in the path of the forward

or advance end of said stakes at the opposite side of the loom are the flared ends 80 of spring fingers 81 which are partially flexed or spread by said stakes as the stakes engage them, to cushion the suddenly arrested travel of the stakes and prevent their rebound. Said fingers however, are so disposed as to permit not only the withdrawal of the stakes therefrom as the fabric is formed, but also so that they in no manner interfere with the straightening action of the air jets before described. The springs 81 are carried by an L-shaped longitudinally slotted plate 82 mounted on one of the guide bars for the heddle plates 24, and this plate 82 is adjustable laterally to accommodate stakes of different lengths for fabrics of different widths. The relative positions of the stake inserting and stake cushioning and rebound preventing means just above described, with respect to each other and to the side plates 1-1 of the loom is best illustrated in Fig. 35.

The loom of course is made of a width to weave fabric of maximum width required in the industry. However, there are times when fabric of less than the maximum widths are desired and with the looms as heretofore made, it has been the practice to pull or withdraw from the loom such strands as were not actually used in the fabric produced. This pulling of the strands is objectionable because when a maximum width fabric is again desired to be produced, the pulled strands must be rethreaded into and through the heddle bars which is a slow, laborious and expensive task.

In my improved loom, fabric of any desired width less than maximum may be produced without pulling any warps, simply by employing any suitable tool to manually shift the desired neck bars into a perpendicular or neutral position wherein they cannot be engaged by the flange 21 of either bar 14 and 20 respectively. Thus even though said bars are reciprocating, they in no manner actuate the neck bars which are in neutral position so that the associated heddles remain passive and inoperative. To again return the heddle plates to operation, it is only necessary to restore the naturally positioned neck bars so that they will again become actuated by the flanges 21 of said bars 14 and 20. This structure provides the utmost flexibility in a loom for this purpose wherein any desired heddle plate may be thrown out of operation at any time and held out of operation so long as it is desired and this without pulling the associated strands from the loom with subsequent rethreading.

Thus it is apparent that in the construction described, it is only necessary to employ pattern cards commensurate with the width of the pattern desired in the fabric, thereby

simplifying the making of such pattern cards.

Furthermore it is often desired to weave regular over and under strand fabric with only a band or ribbon extending the full length thereof. In this respect, the pattern chain mechanism can be rendered inoperative in several different ways as for instance by removing all cards therefrom. With alternate neck bars positioned to be engaged by the flange 21 of one bar (14 or 20) and the intermediate neck bars positioned to be engaged by the flange 21 of the other bar (20 or 14) it is only necessary to shift those neck bars into side by side relation at that point where the band is desired in the fabric and start the loom into operation.

Again with the use of the chains 69 with the cam elements 68, the operation of the card chain sprockets 50 may be controlled so that desired patterns may be repeated at will as often as desired or may be rendered inoperative for the desired period of time. In this manner the length of pattern chain required is reduced to a minimum.

For some fabrics having an extensive variable design pattern chains are necessary of a length such that they cannot conveniently hang as shown in Fig. 4 and in that event means are provided for supporting the chains which means are shown in Figs. 33 and 34.

Thus, secured to the upper part of the machine, at each side are two pairs of members 150 and 151 the members of each pair diverging upward and being connected near their upper ends by spacer bars 152 and 153 respectively. Transverse tie rods 154 and 155 secured by nuts as shown complete the frame assembly.

At the ends of the frame are swinging brackets 156 and as they are alike in construction a description of one will suffice for both. At the upper end the bracket is mounted upon a cross rod 157 which in turn is swingably mounted in bearings 158 in the frame.

The lower end of the bracket 156 supports an idler sprocket 159 through the medium of the cross rod 160.

In order to take up the slack in the pattern chain and to permit the main sprocket members 50 to move toward and away from one another as required during the operation of the machine, arms 161 are clamped to the transverse rod 157, the other ends of which in turn are connected to the frame by the tension spring 162. To provide for adjustment of the tension the arm 161 is provided with a plurality of openings 163 in any of which the end of the spring 162 may be secured.

As a further means of accommodating pattern chains of various lengths the frame members 150 and 151 are provided with spaced bearings 158^a and 158^b so that the swinging bracket 156, as a whole, may be

moved to various positions. Of course, the arms 161 and springs 162 will be correspondingly moved when the brackets 156 are moved.

The above mechanism provides great flexibility as to length of pattern chain which can be properly used in the machine.

I claim as my invention:—

1. In a loom, reciprocable heddle members, alternate ones of which are of one length and intermediate ones of which are of another length, neck bars means providing a swingable connection between said neck bars and said alternate and intermediate heddle members, the neck bars connected to the intermediate heddle members being of a length greater than those connected to the alternate heddle members whereby the connection between alternate heddle members and the associated neck bars cannot register with the connection between the intermediate heddle members and their associated neck bars in the reciprocation of said heddle members. 75 80 85

2. In a loom, heddle bars arranged in pairs with one bar of each pair of a length greater than the other, a pair of neck bars associated with each pair of heddle bars, one of said neck bars being of length greater than that of the other, and means for swingably connecting the longer neck bar to the shorter 15 heddle bar and the shorter neck bar to the longer heddle bar whereby the said means associated with the longer heddle bars and shorter neck bars cannot register with said means associated with the shorter heddle bars 100 and the longer neck bars in the reciprocation of said heddle bars.

3. A heddle bar for a loom comprising an elongated flat plate like member having a diagonally disposed warp receiving slot therein opening through opposite edges thereof, there being a part of said member offset to one side thereof and bridging said slot. 105

4. In a loom, heddle bars arranged in pairs and each comprising an elongated flat plate like member having a diagonally disposed warp receiving slot therein, which opens through opposite edges thereof, the slot in one plate being disposed at an angle to that of the other and each slot having a bridge part crossing the slot, each plate also having an elongated opening adjacent the slot to receive the bridge part of the slot in the other plate. 115

5. In a loom, a shedding mechanism comprising heddle bars and neck bars swingably connected thereto, a reciprocating neck bar actuating member and means for swinging said neck bars about the connection with the heddle bars into position to be engaged by said actuating member, said means being so formed as to be capable of actuation to permit a manual shifting of desired neck bars into a neutral position with respect to the neck bar actuating member. 120 125 130

6. In a loom, a shedding mechanism comprising heddle bars and neck bars swingably connected thereto, a reciprocating neck bar actuating member disposed on each side of the neck bars and means for swinging the desired neck bars about the connection with the heddle bars from engagement with one actuating member to the other and vice versa, said means including parts capable of manual manipulation to move any desired neck bar into a position neutral with respect to both actuating members.

7. In a loom, a plurality of vertically reciprocable heddle bars, neck bars swingably connected thereto, shifter members one engaged with the top end of each neck bar and movable in a plane at a right angle to the heddle bars, said shifter members being arranged in sets and each having end extensions with the extensions of one member staggered with respect to the extensions of another member of the set.

8. In a loom, a heddle plate, a neck bar swingably connected at one end thereto, a shifter member movable in a plane at a right angle to said neck bar and formed between its ends to operatively engage the other end of the neck bar.

9. In a loom, a neck bar shifter member comprising a plate having an extension on each end and formed along one side at a point between said ends to be operatively engaged with an associated neck bar.

10. A loom embodying therein a plurality of alternate and intermediate heddle plates arranged side by side, each of said heddle plates being provided with a strand guide slot extending angularly of its side edges, the said slots of alternate heddle plates extending at a substantial angle to those in said intermediate plates.

11. A loom including alternate and intermediate reciprocable heddle plates each having an angularly disposed strand guide slot therein and, means for reciprocating said sets in opposite directions simultaneously, said guide slots of alternate heddle plates being disposed in intersecting relation with respect to those in the intermediate ones.

12. A loom including thin, flat individual heddle plates arranged in pairs, the plates of each pair provided with relatively oppositely inclined strand guide slots extending from one side edge to the other thereof.

13. A loom including heddle plates arranged in pairs, the plates of each pair provided with relatively oppositely inclined strand guide slots, extending from one side edge to the other thereof, a bridge element spanning each of said slots at the side of each plate opposed to the companion plate, there being longitudinal slots in said plates for receiving said bridge elements.

14. A loom including a series of reciprocating heddle plates each of substantially the

thickness equal to the diameter of a strand, each of said plates being provided between its ends with an angularly disposed strand guide slot, the slot of one plate crossing the slot of the companion plate, and a bridge element spanning the slot of each plate at the side thereof opposed to the companion plate, there being a longitudinal slot in each plate to accommodate the said bridge element of the other.

15. A loom including a series of reciprocable heddle plates each provided with a strand guide slot, means associated with said series of heddle plates for simultaneously reciprocating selected groups thereof in respectively opposite directions, take up rolls associated with said heddle plates and cooperating therewith to form sheds, means for inserting a stake into each shed as it is formed and fluid pressure means for positioning and straightening the stakes in the sheds.

16. A loom including a series of reciprocable heddle plates each provided with a strand guide slot, means associated with said series of heddle plates for simultaneously reciprocating selected groups thereof in respectively opposite directions, take up rolls associated with said heddle plates and cooperating therewith to form sheds, means for inserting a stake into each shed as it is formed and means for projecting compressed air jets against the stakes to thereby laterally move the same into contact with the heddle plates to straighten the same and position them in the sheds.

17. A loom including a series of reciprocating heddle plates each of substantially the thickness equal to the diameter of a strand, each of said plates being provided between its ends with an angularly disposed strand guide slot, the slot of one plate crossing the slot of the companion plate, take up rolls associated with said heddle plates for forming sheds, means associated with said heddle plates for simultaneously reciprocating selected groups of said plates in respectively opposite directions, said relative arrangement of strand guides of said plates preventing lateral movement of strands when a closely grouped series of said plates are held

against movement relatively to each other, and mechanism operatively associated with said plates for automatically selecting the plates to compose each of said oppositely reciprocating groups.

18. A loom including two series relatively reciprocable heddle plates equipped with strand guide slots and having front edge portions arranged flush with each other to provide a plain surface forming a wall of a shed, take up rolls associated and cooperating with said heddle plates to form sheds, mechanism for projecting stakes into said sheds, and fluid pressure means arranged to project said

stake against said plain surface to straighten and position the same in the shed.

19. A loom including relatively reciprocable sets of heddle plates equipped with strand guide slots, the latter relatively arranged in alternate plates to cause the latter to maintain the strands continuously housed in said guides, means for reciprocating said respective sets of plates simultaneously in respective opposite directions and mechanism associated with said plates for automatically shifting selected groups of plates from one of said sets to the other thereof.

20. A loom including two sets of relatively reciprocable heddle plates, a neck bar for each plate, two simultaneously oppositely reciprocable members, means on each neck bar for engaging either of said members, a reciprocable shift plate associated with each neck bar for throwing the latter into engaging relation to one of said members, pattern chains and sprockets operatively associated with said shift plates for determining their relative positions, reciprocable means for actuating said shift plates and cooperating with said pattern chains and sprockets to selectively control the shift of certain groups of said heddle plates and their neck bars from one of said sets of the other thereof, cooperating means on said reciprocable means and said sprockets for rotating the latter at intervals, a traveling member associated with said cooperating means, and a series of cam element detachably mounted on said traveling member for successive engagement with said cooperating means to throw the latter out of engaging relation to the sprocket at predetermined intervals.

21. A loom including two sets of relatively reciprocable heddle plates, a neck bar for each plate, two simultaneously oppositely reciprocable members, means on each neck bar for engaging either of said members, a reciprocable shift plate associated with each neck bar for throwing the latter into engaging relation to one of said members, pattern chains and sprockets operatively associated with said shift plates for determining their relative positions, reciprocable means for actuating said shift plates and cooperating with said pattern chains and sprockets to selectively control the shift of certain groups of said heddle plates and their neck bars from one of said sets of the other thereof, cooperating means on said reciprocable means and said sprockets for rotating the latter at intervals, and a sprocket chain equipped with detachable cam elements arranged for controlling the engaging relation of said cooperating means with said sprockets at intervals determined by the said cam elements.

22. A loom including two sets of relatively reciprocable heddle plates, a neck bar for each plate, two simultaneously oppositely re-

ciprocable members, means on each neck bar for engaging either of said members, a reciprocable shift plate associated with each neck bar for throwing the latter into engaging relation to one of said members, pattern chains and sprockets operatively associated with said shift plates for determining their relative positions, reciprocable means for actuating said shift plates and cooperating with said pattern chains and sprockets to selectively control the shift of certain groups of said heddle plates and their neck bars from one of said sets of the other thereof, pins on said sprockets, hook bars on said reciprocable means for engaging said pins to rotate said sprockets, a plunger disposed in operative relation to said hook bars for throwing the same out of engaging rotation to said sprockets, a sprocket chain arranged for travel approximate to said plunger, and cam elements detachably mounted on said sprocket chain for engaging said plunger at predetermined intervals to thereby throw said hook bars out of engaging relation to said sprockets.

23. In a loom, a plurality of flat plate like heddle bars arranged in close side by side engagement and each formed in the plane of its edges for the passage of a strand therethrough, means engaged by said edges to provide sliding guiding bearing for said bars, a flat plate like neck bar operatively connected at one end to an associated heddle bar for a swinging movement in the plane of its edges to one side or the other of the median plane of its associated heddle bar, and a reciprocating actuating bar common to all of said neck bars and adapted to engage and actuate said neck bars when said neck bars are in a position to one side of the median plane of the heddle bars.

24. In a loom, a plurality of flat plate like heddle bars arranged in close side by side engagement and each formed in the plane of its edges for the passage of a strand therethrough, means engaged by said edges to provide sliding guiding bearing for said bars, a flat plate like neck bar operatively connected at one end to an associated heddle bar for a swinging movement in the plane of its edges to one side or the other of the median plane of its associated heddle bar, and a reciprocating actuating bar on each side of all the neck bars and adapted to actuate said neck bars when said neck bars are swung to one side or the other or the median plane of the heddle bars.

25. In a loom, a plurality of flat plate like heddle bars arranged in close side by side engagement and each formed in the plane of its edges for the passage of a strand therethrough, means engaged by said edges to provide sliding guiding bearing for said bars, a flat plate like neck bar operatively connected at one end to an associated heddle bar

for a swinging movement in the plane of its edges to one side or the other of the median plane of its associated heddle bar, and a reciprocating actuating bar on each side of all 5 of the neck bars, said neck and actuating bars having coacting flanges and recesses adapted for engagement when said neck bars are swung to one side or the other of said median plane, whereby movement is imparted to said neck bars from said actuating bars, the recesses being of a dimension greater in one 10 direction than that of said flanges.

26. In a loom, a plurality of flat plate like 15 heddle bars arranged in close side by side arrangement and each formed in the plane of its edges for the passage of a strand therethrough, means engaged by said edges to provide sliding guiding bearing for said bars, a flat plate like neck bar having a recess in 20 each edge, operatively connected at one end to an associated heddle bar for a swinging movement in the plane of its edges to one side or the other of the median plane of its associated heddle bar and a reciprocating bar on 25 each side of all the neck bars and having a flange of a depth less than that of the recesses into which they extend when the neck bars are moved to one side or the other of said median plane of the heddle bars to impart movement 30 to said neck bars.

27. In a loom, a plurality of flat plate like 35 heddle bars arranged in close side by side engagement and each formed in the plane of its edges for the passage of a strand therethrough, means engaged by said edges to provide sliding guiding bearing for said bars, a flat plate like neck bar operatively connected at one end to an associated heddle bar for a swinging movement in the plane of 40 its edges to one side or the other of the median plane of its associated heddle bars, a reciprocating actuating bar spaced to each side of the median plane and adapted for engagement with desired neck bars when the same 45 are swung to one side or the other of said median plane but inoperative to actuate said neck bars when they stand in said median plane and means operating upon the other end of said neck bars for swinging the same 50 to one side or the other of said median plane.

28. In a loom, a plurality of flat plate like 55 heddle bars arranged in close side by side engagement and each formed in the plane of its edges for the passage of a strand therethrough, means engaged by said edges to provide sliding guiding bearing for said bars, a flat plate like neck bar operatively connected at one end to an associated heddle bar for a swinging movement in the plane of its 60 edges to one side or the other of the median plane of its associated heddle bars, a reciprocating actuating bar spaced to each side of said median plane and adapted to be engaged by desired neck bars when the same are swung 65 to one side or the other of said median plane

and a shifter associated with the other end of each neck bar and movable in a plane at a right angle to said median plane to swing each neck bar to one side or the other of said median plane, said neck bars being capable 70 of being manually moved into said median plane and out of actuating engagement by said reciprocating bars.

29. In a loom, a plurality of flat plate like 75 heddle bars arranged in close side by side engagement and each formed in the plane of its edges for the passage of a strand therethrough, means engaged by said edges to provide sliding guiding bearing for said bars, alternate heddle bars being longer than the intermediate ones, a neck bar associated with each heddle bar, the neck bars associated with the alternate heddle bars being shorter than those associated with the intermediate ones, means providing arcuate head and recess 80 connections between said heddle and neck bars whereby the neck bars are swingable to one side or the other of the median plane of said heddle bars and an actuating bar on each side of all the neck bars adapted to be engaged 85 thereby when swung to one side or the other of said median plane, the difference in length of said heddle and neck bars insuring non-registration of the said arcuate head and recess connection between alternate and intermediate heddle and neck bars. 90

30. In a loom, a plurality of heddle members, neck bars swingably connected to said heddle members and a reciprocating member disposed on each side of said neck bars, certain ones of which neck bars are engaged with one reciprocating member and the other neck bars being engaged with the other reciprocating member, said neck bars and reciprocating members being formed for a relative 100 lost motion during a part of the reciprocation of said members in one direction. 105

31. In a loom, shed forming mechanism, means for inserting a weft into each shed as it is formed and fluid pressure means operating in a plane other than parallel with the weft for straightening the weft after insertion in the shed. 110

32. In a loom, shed forming mechanism, means for inserting a weft into each shed as it is formed and fluid pressure means operating upon the weft in a plane other than parallel with the weft to straighten the weft after insertion in the shed but before the same 115 is bound in place therein. 120

33. In a loom, shed forming mechanism, including a plurality of adjacent heddle bars, means for inserting a weft into each sheet as it is formed and fluid pressure means for moving the weft against the edges of said heddle bars to straighten the weft before it is bound in place by the formation of the next 125 shed.

34. In a loom, shed forming mechanism, including a plurality of adjacent heddle bars, 130

means for inserting a weft into each shed as it is formed and means providing jets of air discharging against said weft to force it against the edges of said heddle bars to straighten the weft before it is bound in place by the formation of the next shed.

35. In a loom, shed forming mechanism, means disposed at one side of said mechanism for inserting a weft into each shed as it is formed and means disposed at the other side of said mechanism adapted for engagement by the stake being inserted to cushion the insertion thereof and prevent its rebound, but permitting its movement out of the same in a direction at a right angle to the plane of said insertion upon the formation of the next shed.

36. In a loom, shed forming mechanism, means disposed at one side of said mechanism for inserting a weft endwise into each shed as it is formed and means comprising yielding spring fingers disposed at the other side of said mechanism adapted to be engaged by the advancing end of the weft and to cushion the insertion of said weft and to prevent its rebound, said means being so formed as to permit a withdrawal of the weft therefrom in a plane at a right angle to that of its insertion.

37. In a loom, shed forming mechanism, means disposed at one side of said mechanism for inserting a weft into each shed as it is formed and means disposed at the other side of said mechanism adapted to cushion the insertion of the weft and prevent its rebound, said means being adjustable in the plane of the insertion of said weft.

38. In a loom including two series relatively reciprocable heddle plates equipped with strand guide slots and having front edge portions arranged flush with each other to provide a plain surface forming a wall of a shed, take up rolls associated and co-operating with said heddle plates to form sheds, mechanism for projecting stakes into said sheds, and compressed air jets projecting means arranged to project said stake against said plain surface to straighten and position the same in the shed.

39. In a loom, the combination with shed forming means, including vertically reciprocating heddle bars and guides therefor, of mechanism for projecting stakes into successive sheds, and cushioning means supported by one of said guides disposed in the path of said stakes and adapted to be engaged by the advancing end thereof to prevent buckling or rebound of the stakes.

40. In a loom, the combination with shed forming means, including vertically reciprocated heddle bars and guides therefor, of mechanism for projecting stakes into successive sheds, and cushioning means supported on one of said guides disposed in the path of said stakes and adapted to be engaged by

the advancing end thereof to prevent buckling or rebound of the stakes and stake straightening and positioning means arranged for operation the instant following projection of a stake into a shed.

41. In a loom, the combination with shed forming means, of mechanism for projecting stakes into successive sheds, and cushioning means disposed in the path of said stakes to prevent buckling or rebound of the stakes and nozzles arranged to project compressed air jets against the stakes instantly following projection thereof into the sheds for positioning and straightening said stakes in the paths.

In testimony whereof, I have hereunto set my hand, this 22nd day of Nov., 1929.

SIMON BOLIN.
